MACHINE FOR CARROTING FURS

Filed Oct. 21, 1930

UNITED STATES PATENT OFFICE

JOSEPH WEBER AND JULIAN F. TOMAINO, OF DANBURY, CONNECTICUT

MACHINE FOR CARROTING FURS

Application filed October 21, 1930. Serial No. 490,186.

This invention relates to new and useful improvements in machines for treating fur either to carrot or dye it.

An object of the invention is to provide a machine for the purpose stated and which includes means for spraying the carrotting or dyeing material on to the fur, said means being so arranged as to prevent drops of the material getting onto the fur.

Another object is to provide a carrotting or dyeing machine wherein the carrotting or dyeing material is sprayed onto the fur to be treated, means being provided whereby the angle of the spray relative to the fur may be changed as and when required.

A further object is to provide a carrotting or dyeing machine including means whereby the carrotting or dyeing material is sprayed through the use of compressed air, means being provided whereby the position of the spraying means may be adjusted either to vary the angle at which the spray is applied to the fur or to vary the position of the spraying means relative to the fur.

A further object is to provide a carrotting or dyeing machine including means for feeding a liquid carrotting or dyeing material to a point above the fur to be treated, and including means directing compressed air beneath the point of delivery of the liquid whereby the liquid is taken up by the air spray and drops of the liquid prevented from getting on to the fur.

An additional object is to provide a fur carrotting or dyeing machine including means for applying a continuous spray across the entire width of the fur bearing skin whereby the fur is uniformly treated.

Other objects and advantages will become apparent from a consideration of the following detailed description taken in connection with the accompanying drawing wherein one satisfactory embodiment of the invention is shown. However, it will be under-

stood that the description and drawing are for the purpose of disclosure and that the invention is not limited to the details shown, since changes in construction, combination and arrangement of parts may be made without departing from the spirit of the in-

vention or the scope of the appended claims to which reference must be had for a definition of the limitations of the invention.

In the drawing:

Fig. 1 is a central longitudinal sectional view substantially on the line 1—1 of Fig. 2;

Fig. 2 is a plan view of the entire machine, a section of the air drum of the spraying means being cut away;

Fig. 3 is a detail sectional view of a portion of the means for supplying air to the spray, the view being taken substantially along the line 3 of Fig. 1; and

Fig. 4 is a side elevational view showing some of the driving mechanism used in the machine.

Referring in detail to the drawing, the operating parts of the machine are shown as mounted upon a table or support 5 including supporting legs 6 and 7, side rails 8 and 9, and supporting surfaces 10 and 11 extending between and secured to the side rails 8 and 9. At the rear edge of the supporting surface or top 10 are a pair of corrugated feed rolls comprising upper and lower rolls 12 and 13 driven from a suitable source of power as will presently be described.

Spaced rearwardly of the rolls 12 and 13 are a pair of feed rolls comprising upper and lower corrugated rolls 14 and 15 respectively. As shown the upper rolls 12 and 14 have their shafts 16 and 17 respectively, disposed to operate in suitable bearings 18 secured on the upper edges on the side rails 8 and 9. Thus it will be seen the feed rolls span the space between the rails 8 and 9. The lower feed rolls 13 and 15 are mounted to align with the upper feed rolls 12 and 14 respectively and these lower feed rolls are also mounted in the side rails 8 and 9 by any suitable means.

Mounted between the front and rear sets of feed rolls is a sheet or plate of glass 19, this sheet or plate substantially filling the space between the sets of feed rolls and extending from one of the side rails 8 and 9 to the other thereof. Any suitable means may be used for mounting the plate 19. As shown this means includes brackets 29 se-

cured to the rails 8 and 9 as by means of screws 21.

A pair of brackets 23 and 24 are mounted on the rails 8 and 9 rearwardly of the feed 5 roll 14. These brackets are so mounted as to have a limited movement longitudinally of the rails and to this end each of the brackets is slotted as at 25 and secured to its respective rail by means of a bolt 26 carrying a nut 27. As shown the rails 8 and 9 have greater height adjacent their rear ends whereby shoulders 28 are formed. Each of these shoulders 28 carries a short forwardly projecting pin 29 and a corresponding pin 30 is carried by the upwardly extending rear portion 31 of the brackets 23 and 24. Interposed between the shoulders 28 and the portions 31 of the brackets, and having their end portions disposed 15 about the respective pins 29 and 30 are a pair of coil springs 32. These springs 32 normally urge the brackets 23 and 24 in the direction of the feed roll 14 and permit of movement in said brackets in a direction 20 away from the feed roll.

At its forward end each of the brackets 23 and 24 carries an upstanding portion 33 reinforced by web 34 as shown. The upper ends of the portions 33 are enlarged to provide 30 bearings 36 wherein are mounted the end portions of a shaft 37 carrying a roll 38. In the art this roll 38 is known as a "slicking" roll. Roll 38 is driven from the shaft 17 of the roll 14 and as shown the 35 driving means includes a relatively large pulley 39 on the shaft 17 and a relatively small pulley 40 on the shaft 37, an endless belt 41 being disposed over the two pulleys. Owing to the difference in the size of the 40 pulleys 39 and 40 it will be apparent that roll 38 will be driven faster than will the roll 14, and the purpose of this difference in speed will later be described in detail.

The driving means for the different parts 45 may comprise an arrangement as shown although it will be understood that different lay-outs for this purpose could be used. From any suitable source of power the shaft 42 is driven and this shaft carries a set of 50 pulleys 43 of different sizes. Above the shaft 42 and supported by the side rail 9 is a relatively short shaft 44 provided with a set of pulleys 45, the pulleys of the set 45 being arranged in reverse relation to the 55 pulley of the set 43. An endless belt 46 is used for transmitting power from the pulleys 43 to the pulleys 45 and it will be apparent that the belt may be shifted on the pulleys to have the shaft 42 drive the pulleys 43 at the desired speed.

Secured to the shaft 44 inwardly of the pulleys 45 is a gear 47 relatively small in diameter and meshing with and driving gears 48 and 49 secured to the shafts 16 60 and 17 of the rolls 12 and 14 respectively.

The pulleys and gearing just described are shown as arranged at the outer side of the rail 9. At the outer side of the rail 8 the shafts 16 and 17 carry gears 50 and 51 respectively, these gears 50 and 51 meshing with and driving gears 52 and 53 arranged on the ends of the shafts of the rolls 13 and 15 respectively whereby such rolls are driven in a direction opposite to that in which the rolls 12 and 14 are driven.

Secured to the rear support or table 11 are uprights 54 three of which are shown. These uprights support a receptacle 55 into which is received the neck 56 of a container or bottle 57 carrying the carotting or dyeing liquid. The bottle itself is supported on a rubber or other supporting ring 58 which is constructed to permit entrance of air, and it will be understood that since a flexible tube or pipe 59 is fed from the receptacle 55, as through the opening 56, there will be a steady flow of liquid to such tube or pipe under a constant head or pressure. At its forward end the tube 59 is provided with a T-shaped fitting 61, the branches of which are connected to other sections of flexible tubing 62 and 63 respectively. A tube 64 preferably of glass is disposed transversely of the support and above the glass plate 19, the tube above such plate having at its under side a series of perforations 65.

Brackets 66 are secured to the end portions of the supporting surface or top 10. The brackets are adjustable and to this end each bracket is slotted at 67 for the reception of a bolt 68 carrying a nut 69 by means of which the brackets may be clamped in adjusted positions. As shown the brackets incline at 70 as they extend rearwardly and at its rear end each bracket has an opening for the reception of a stud or short shaft 71 carried by the cap or closure 72 of a relatively large tube 73. It will be understood that owing to its particular mounting in the brackets 66 the tube may be rotated and lag screws or other means 74 are provided for securing the tube in desired adjusted position.

By means of brackets 75 the glass tube 64 may be secured to and supported by the relatively large tube 73. Compressed air is supplied to the tube 73 through the flexible piping or tubing 76. Extending through a wall of the tube 73 are a series of small tubes 77 each having its inner end open as at 78 and each in a side wall of its outer end portion being provided with an orifice 79. There is one tube 77 provided for each of the openings or orifices 65 in the tube 64 and the tubes 77 are so arranged that their openings or orifices 79 are disposed slightly beneath the openings or orifices 65 of the tube 64. With the construction described it will be understood that the air pressure throughout the tube 73 will

be the same and that accordingly the air issuing through each of the orifices 79 of the tubes 77 will be under the same pressure.

5 A conveyor in the form of an endless belt 80 operates to receive the carotted or dyed furs and carry them from the machine. This belt 80 operates over a roll 81 secured in a bearing member 82 carried by 10 the underside of the rails 8 and 9. The belt 80 also operates over a roller 83 mounted in bearings in brackets 84 secured to the upright 7. The roller 83 has its shaft 85 extending beyond one of the brackets 84 15 and carrying a pulley 86 over which is trained a driving belt 87 driven as by a pulley 88 on the end of the shaft 16. It will be noted that the conveyor 80 extends rearwardly of the feed rolls 14 and 15 and 20 when treated furs pass from these rolls they will be received on the conveyor and delivered by the latter to a second conveyor if desired or to a receptacle 89.

In the operation of the improved machine furs are fed either by hand or otherwise across the support 10 to the first set 25 of feed rolls comprising the rolls 12 and 13. For the purpose of the present machine the skins are fed with their fur side up and 30 as they are pushed along or fed along across the plate 19 by the rolls 12 and 13 they are sprayed with the carressing or dyeing material. Owing to the use of a plurality of 35 openings or orifices in the tubes 64 and in the tubes 77 the treating material is applied to the furs in the form of a sheet of mist.

Owing to the angle at which the spray is applied it gets under the fur fibres raising them up as suggested in the drawing 40 whereby the material penetrates to the roots of the fibres. Since the sheet of mist or the spray is substantially the width of the plate 19 and of uniform pressure throughout it will cover the entire width of the fur bearing skin and accordingly the fur will be 45 uniformly treated.

Since the air orifices 79 in the tubes 77 are disposed below the orifices 65 in the tubes 64 for the liquid it will not be possible for 50 drops of the carressing or dyeing liquid to fall onto the fur and burn it, as such drops would be required to pass through a continuous air blast. This air picks up and finely divides any liquid dropping into it. With 55 our present arrangement the jets of air extend below and across the orifices 65 and accordingly all of the liquid is taken up in the air. This is an important feature of our device as giving a uniform treatment to 60 the fur and preventing damage to it by too much carressing liquid at any spot. After the treated furs pass across the plate 19 they are engaged by the feed rolls 14 and 15 and 65 drawn along beneath the spray. Should a fur bearing skin tend to turn upwardly with

the upper feed roll 14 it will be pushed back off such roll by the "slicking" roll 38 which as previously described rotates at a higher speed than does the feed roll.

Since the "slicking" roll is resiliently 70 mounted due to the employment of the springs 32 it may move toward and from the feed roll to accommodate furs of different thicknesses. Also, the spraying means may be adjusted to vary the angle at which 75 the spray engages the fur, it simply being necessary to loosen the screws 34 and turn the drum or tube 73 a slight distance about its axis. Further, the drum itself may be bodily adjusted by loosening the nuts 69 and 80 moving the brackets 68 forwardly or rearwardly. As the treated furs leave the feed rolls 14 and 15 they will fall down onto the conveyor 80 and be carried from the machine in a manner already described. 85

Owing to the fact that the material used in treating the furs may be poisonous and corrosive and to prevent the spread of the sprayed material where it might be inhaled by the workmen the entire machine is enclosed in a glass case or housing (not shown). Also, while the machine has been described as for the purpose of carressing or 90 dyeing furs and particularly with relation to carressing, it is to be understood that the invention is not limited to the particular uses stated and further that while the invention is shown as being used on fur bearing skins some features of it would be applicable to the treating of fur after the same 95 has been removed from the skin. Therefore, wherein the following claims the machine is described as a carressing machine it is to be understood that it is intended to cover the machine for other purposes. 100

Having thus set forth the nature of our invention, what is claimed is:

1. In a machine for treating fur, a tube above the fur, means for supplying compressed air to said tube, a second tube above 110 said fur, means for supplying a liquid to said second tube, said second tube having a series of outlet openings in one of its walls, a series of tubes extending from said first tube to a point below the openings in the second tube, one tube of each of said series of tubes aligned with each of the openings in the second tube, said tubes of said series of tubes receiving air from the first tube, and each of the tubes of said series of tubes having an outlet opening, the outlet openings in said tubes of said series of tubes being disposed below the outlet openings in the second tube whereby to direct jets of air across the outlet openings of the second tube. 115

2. In a machine for treating fur, a relatively large tube above said fur, means for supplying compressed air to said tube, a second tube above said fur, means for supplying a liquid to said second tube, said second

- tube having a series of outlet openings in one of its walls, a series of tubes communicating with the interior of the first tube and each having an outlet and said outlets disposed below the outlets in the second tube, each tube of said series of tubes being aligned with one of the outlets in the second tube whereby jets of air will be directed across the outlets of the second tube, and said tubes being so arranged that the liquid from the second tube is taken up by the air jets and the resulting spray directed on to the fur. 5 70
3. In a machine for treating fur, a relatively large tube above said fur, means for supplying compressed air to said tube, a second tube above said fur and adjacent said first tube, means for supplying a liquid to said second tube, said second tube having a series of outlet openings in one of its walls, 15 80
- 20 a series of tubes communicating with the interior of the first tube, there being one tube in said series for each of the outlets in the second tube and one of the tubes of said series being associated with each of the outlets in said second tube, said tubes extending to a point beyond the outlet in the second tube, an outlet opening in each of the tubes of said series of tubes, said outlet openings in the tubes of said series being disposed below the outlet openings in the second tube and in position to direct jets of air across and below the outlet openings in the second tube and in the direction of the fur, and means mounting said first tube for rotary 25 90
- 30 35 adjustment whereby the angle of said jets relative to the fur may be adjusted. 100
4. In a machine for treating fur, a blower comprising a horizontally extending tube, a plurality of spaced tubes of smaller diameter each extending transversely through a side of the first tube to a point adjacent the opposite side thereof and having an inlet opening, each of said transverse tubes also having a discharge opening outside the first 40 105
- 45 tube, a liquid supply tube extending longitudinally of and adjacent the horizontal tube above the discharge openings from the transverse tubes and having openings to discharge liquid from above on to the air blast from 50 110
- 55 the discharge openings, means for supplying air under pressure to the large tube, and means for presenting the fur to be treated to the blast. 115
5. In a machine for treating fur, a horizontally extending tube, means for supplying compressed air to said tube, a second horizontally extending tube, means for supplying a liquid to said second tube, said second tube having a series of outlet openings in its lower wall, a series of smaller tubes extending transversely through a wall of the first tube, each tube of said series being aligned with one of the openings in the second tube and each having an inlet 60 120
- 65 opening within the first tube and an outlet 125
- 65 130
- opening directed across and below its aligned opening in the second tube to direct an air blast to receive liquid from said aligned opening in the second tube, and means for presenting the fur to be treated to the series of air blasts. 70
- In testimony whereof we affix our signatures.
